CLAIM

The ornamental design for a display rack, as shown and described.

DESCRIPTION

FIG. 1 is a perspective view of a display rack showing my new design;

FIG. 2 is a top plan view thereof;

FIG. 3 is a right side elevational view, the left side being a mirror image thereof;

FIG. 4 is a rear elevational view thereof;

FIG. 5 is a front elevational view thereof;

FIG. 6 is a perspective view of a second embodiment of that shown in Figure; and,

FIG. 7 is a right side elevational view, the left side being a mirror image thereof.

The rear and front elevational views of the second embodiment are the same in appearance as those of the first embodiment.

Fig. 2

*Fig. 3**Fig. 4**Fig. 5*

*Fig. 6**Fig. 7*
